United States Patent Office.

JAMES A. MORRELL, OF CHICAGO, ILLINOIS.

Letters Patent No. 70,788, dated November 12, 1867; antedated October 16, 1867.

IMPROVEMENT IN MACHINES FOR SETTING UP STAVES IN BARRELS.

The Schedule referred to in these Letters Patent and making part of the same.

TO ALL WHOM IT MAY CONCERN:

Be it known that I, JAMES A. MORRELL, of the city of Chicago, in the county of Cook, and State of Illinois, have invented a certain new Machine for Setting Up and Trussing Barrels; and I do hereby declare that the following is a full, clear, and exact description thereof, reference being had to the accompanying drawings, making a part of this specification, in which—

Figure 1 is a side view, with a portion of the staves removed, showing a portion of the conical centre.

Figure 2, a top view, with several staves inserted.

Figure 3, a top view of the hoop-supporter.

Figure 4 is a side view of the same, and

Figure 5 a view of one of the spring-buttons, enlarged nearly to full size.

Like letters refer to the same parts in all of the figures.

The nature and object of my invention consist in constructing a machine for setting up and trussing barrels, by constructing a conical centre which will hold the hoop-supporters in place, and support a truss-hoop so that its interior surface will be free to receive the staves and hold them on the outside; in providing such centre with spring-buttons, to support and hold them on the inside; in providing the machine with a base, to support and hold the bottom of the barrel in place, so that the barrels set up and trussed in this machine will be of uniform size, as the springs will keep the staves full against the truss-hoop and the band of the base, and, in machine-cut and dressed staves, present the ends even and uniform, and, when not so dressed, they will be even at one end.

To enable others skilled in the art to make and use my invention, I will proceed to describe its construction and operation.

The conical or cylindrical centre A is made of heavy staves or segments of wood, held together by the hoops d. For ordinary barrels it is made about two feet and six inches high, about one foot in diameter at the top, and one foot and six inches at the bottom. It can, however, be made cylindrical, or with the ends of the same or nearly the same diameter. It stands upon a circular base, B, which is about two feet in diameter, and surrounded with a band or flange, C, which projects about half an inch above it. In operation, it will be found beneficial to set this base upon a platform provided with a central pin or supporting post, so that it will revolve. At the upper end of the conical centre, I attach to the inside three or more hoop-supporters, D, which are made of iron, and project above the top about five inches, and extend downwards from six to eight inches. They are inserted in grooves or slots, h, (fig. 2,) and held in place by means of a hook or staple-headed bolt, f, which is provided with a nut on the outside of the conical centre, by means of which they are held in place. Thus supporters of different sizes can be readily used. The upper ends of these supports are carried outwards, and extended down so as to support the truss-hoop F at a proper distance from the base B. The outer portions E of these supports are hinged near the middle of the horizontal portion by the hinge b, and held in place by the bar or lock a. This bar or lock may be made in the form shown, or in any other convenient manner. By this arrangement of the supports, the machine can be accommodated to a variation in the size of the truss-hoops, and by curving the hooks I slightly, the machine can be accommodated to different sizes, and adjusted in height by the staple-bolts f; but I prefer to make separate machines for the different sizes of cooperage. The truss-hoops F are such as are in ordinary use, and made either of wood or iron, and are prevented from rising in use by the pins g. About four inches below the top of the conical centre, I provide it with a row of buttons or button-headed pins, c, which are inserted through the staves or segments of the centre, and project out about   inches. They are inserted loosely in the centre, and are held out in place by coiled or other springs, e, which cause them, in use, to press against the staves H of the barrel, and hold them in place, and against the hoop F and band C. Sixteen of these will usually be found sufficient. It will be obvious, however, that their number will be increased or diminished, as well as the size of the other parts, when the size of the machine is increased or diminished for different classes of work.

In operation, the truss-hoop F is placed in the supports D E, which are then locked or fastened by the bars or locks a, which are simply turned on. The upper ends of the staves are then inserted under the hoop, pressed against the buttons c, and, when the lower ends are brought within the band C, pressed down on to the base B.

When the hoop is full, the locks *a* are turned to one side, and the hinged portion *E* of the supports turned up, and the truss-hoop driven down so that it will hold the staves firmly. The barrel is then lifted off from the machine, and finished in the usual manner.

By the use of this machine, boys, and persons not skilled in the art, can set up and truss barrels with ease and rapidity, and those who are skilled, with increased rapidity and ease.

Having thus fully described my machine, what I claim as new, and desire to secure by Letters Patent, is—

1. The buttons *c*, provided with the springs *e*, substantially as and for the purposes specified.
2. The adjustable truss-hoop supporter *D E*, constructed and operating substantially as set forth.
3. The hoop or band *C*, for keeping in place and supporting the lower ends of the staves, substantially as specified.
4. The lock or stop *a*, for holding the truss-hoop supporters in place, substantially as described.
5. The standard or cylinder *A*, base *B*, and buttons *c*, in combination with the truss-supports *D E* and truss-hoop *F*, substantially as and for the purposes specified.

JAMES A. MORRELL.
